ELECTRON DISCHARGE DEVICE

John Henry Owen Harries, London, England

Application August 12, 1936, Serial No. 95,494
In Great Britain May 25, 1936

5 Claims. (Cl. 250—27.5)

This invention relates to electron discharge tubes of the kind described in my United States Patents Nos. 2,045,525, 2,045,526 and 2,045,527, in which the distance between an anode and accelerating electrode is such that the rate of change of the distance curve is positive or not more than slightly negative, the distance curve being the curve relating the distance and the voltage of the anode between the aforesaid electrodes at which the current in the space between them becomes substantially saturated. The invention is particularly but not exclusively concerned with discharge tubes of the above kind in which the distance between the aforesaid electrodes is definitely chosen to be about equal to the distance at which the rate of change of the distance curve is substantially zero. In the above-mentioned patents I have also described valves having their electrodes spaced as above 10 in combination with the use of means for focusing or directing in any desired direction the electrons composing part or parts of the stream; and in which a substantial negative potential gradient between the two electrodes is partly 15 produced by a suitably positioned electrode which is at or about cathode potential.

The object of the invention is to combine the two last-mentioned characteristics, namely, directing the electrons and also producing a negative potential gradient by means of an electrode at or about cathode potential, by means having the advantages of simplicity of manufacture and cheapness and which may readily be freed from 20 occluded gases during the normal manufacturing treatment of the tube.

In order that the invention may be more clearly understood it will now be described by way of example with reference to the accompanying drawing, in which:—

40 Figure 1 is a side elevation of an electron discharge tube, the anode being broken away to show the other electrodes, and

Figure 2 is a plan of Fig. 1.

Figure 3 is a circuit diagram.

45 Figure 4 is a graph showing the relation between the anode auxiliary electrode distance and the breakdown voltage.

Referring now to the drawing, the cylindrical anode 1 is supported by means of rods 2 which 50 are secured at their lower end in the glass press 3. The outer envelope 4 of the tube together with the glass press 3 are carried by a base 5. The auxiliary or accelerating electrode is formed of a pair of rods 6 and 7, one of which rods is 55 secured at its lower end in the glass press 3.

Each of the rods 6 and 7 may be arranged to pass through plates 8 and 9 of insulating material, for example mica, which are carried by the rods 2 for the anode. These plates 8 and 9 serve to retain the auxiliary electrode in position. The auxiliary electrode consists of a wire mesh formed by a winding of wire 10 on the rods 6 and 7, and this may conveniently be given the substantially lenticular cross-sectional shape shown in Figure 2. The control grid comprises a winding of wire 11 on a pair of supports 12 and 13, one of which is retained in position by the insulating plates 8 and 9, and the other of which, 13, extends into the press 3. The auxiliary and control electrodes are of substantially the same 15 length as the anode although in Fig. 1 each is shown as being broken away over substantially half its length to avoid confusion with the other. The cathode 14 may be of the usual construction and may also be supported by means of the plates 20 8 and 9. The filament wires 15 may be respectively connected to leads 16 sealed in the press 3, and the usual leading-in wires for each of the other electrodes may be provided in the known manner.

25 The relative positions of the anode and auxiliary electrodes are determined by the distance curve illustrated in Fig. 4 in which the distance d of the anode from the accelerating electrode is applied against the breakdown voltage E_B , that is to say, the anode voltage at which anode current becomes saturated. From this curve it will be seen that there is a critical distance of the anode from the auxiliary electrode at which the breakdown voltage is a minimum and 30 it is preferred to arrange the anode either at its critical distance or a distance at which the rate of change of the curve is positive or not more than slightly negative, since when the anode is so placed any secondary electrodes which may 35 be omitted from the anode are prevented by a spaced charge from passing back to the auxiliary electrode.

According to the invention, and in the particular form of tube illustrated, four rod-like directing electrodes are positioned in the space between the auxiliary electrode 10 and the anode 1. These rod electrodes 17, which may have substantially the same cross-sectional area as the support rods 6 and 7 or 12 and 13, may be 45 arranged in pairs on either side of the major axis of the auxiliary electrode 10 and may also be suitably supported by passing through holes in the insulating plates 8 and 9. One of the rod electrodes 17 is extended downwards towards the 50 55

press and connected to a lead sealed therein, this lead being also, if desired, connected to the cathode of the valve. In the example shown this latter connection is effected by a wire 18 connecting the cathode to one of the rods 17, all four rods being electrically connected together by further rods 19 and 20 which may be disposed either as shown above the plate 9 or if desired above or below the plate 8.

10 In this type of tube the electron discharge in the absence of the rods 17 passes towards the anode in two more or less fan-shaped beams, there being comparatively little discharge towards the anode in the general direction of the 15 major axis of the control grid and accelerating grid. I have found that this partial spreading of the electron beam has a tendency to reduce the density of the stream between the auxiliary or accelerating electrode and the anode. Since 20 it is essential that the anode should be positioned at the critical distance, that is to say the distance at which the rate of change of the distance curve is positive or not more than slightly negative, a lowered density of the electron stream 25 results in an increased anode diameter. By positioning the rod electrodes 17 so that the electron beam passes therebetween the electrons are constrained to move towards the anode in a comparatively confined path, thus increasing the density 30 of the stream and enabling the anode diameter to be reduced.

In general it may be desirable to position the electrodes 17 outside the area between the control grid and its projection upon the face of the 35 anode.

A further advantageous effect is obtained in that the said rod electrodes 17 assist in the production of a negative potential gradient between the auxiliary electrode 10 and the anode 1, thus 40 further decreasing the anode diameter at which the anode is at the said critical distance.

The type of valve shown in Figures 1 and 2 can be conveniently constructed so as to have the following dimensions—

45 *Cathode*.—1.5 mms. x 1 mm. x 35 mms.
Control grid:
Supports.—1.5 mms. diameter.
Wire winding.—0.1 mm. diameter wire wound 15 turns per cm.

50 *Accelerating grid*:
Support rods.—1 mm. diameter.
Wire winding.—0.1 mm. diameter wire wound 9.5 turns per cm.

55 *Rod directing electrodes*.—0.75 mm. diameter.
The rods of each pair between the accelerating electrode and the anode 1.3 cms. apart.
Distance between the rods of each pair 4.8 mms.

60 *Anode*.—22 mms. diameter. 26 mms. long.
The anode may conveniently be of nickel subjected to a carbonizing treatment.

It may here be mentioned that in an exactly similar valve, excepting only that the rod directing electrodes are omitted, has a critical anode diameter of 27 mms.

Valves constructed according to the invention may be employed in any of the well-known ways, the circuit diagram shown in Figure 3 being typical. In this diagram the input signal to be amplified is applied across the terminals A and B, the terminal A being connected to the control grid 11 whilst the terminal B is connected to the cathode through a resistance shunted by a condenser. The directing electrodes 17 are con-

nected directly to the cathode either externally of the valve or internally. The auxiliary electrode may be held at a positive potential by being connected to the positive pole of a source of direct current, the anode being fed from the same source through the primary winding of an output transformer the secondary of which is used, for example, to energize the speech coil of a loud speaker.

When the rod electrodes 17 are not connected to the cathode within the valve they may be brought out to a separate terminal so that they may be given a potential of the order of the cathode potential, whilst not being connected directly thereto. A valve having the dimensions given above may be employed in the above-described circuit, in which case the following electrical values will be found suitable:—

High tension potential	volts	250
Mean anode current	milliamperes	32
Cathode bias resistance	ohms	250
Shunt condenser	microfarads	25

It must be understood that the above circuit diagram represents a simple form of power output stage, but the valve may be used in other ways, for example a pair of valves may be arranged in push-pull or in any of the other well-known circuit arrangements.

It must also be understood that the invention is not limited to the constructional embodiment above described, which is merely given by way of example, but it also extends to tubes in which the electrodes have different configurations. Further, the rod electrodes, instead of being positioned between the auxiliary electrode and the anode, may in certain cases be positioned between the accelerating electrode and the cathode.

Having now described my invention what I claim as new and desire to secure by Letters Patent is:

1. An electron discharge device comprising a cathode, a control electrode, an auxiliary electrode, an anode spaced from said auxiliary electrode by a distance approximating the distance at which a minimum anode voltage produces anode current saturation, rod-like electrodes independent of said control and auxiliary electrodes for directing electrons in a comparatively confined path toward said anode, and electrical connections between said rod-like electrodes and said cathode.

2. An electron discharge device comprising a cathode, a control electrode, an auxiliary electrode, an anode spaced from said auxiliary electrode by a distance approximating the distance at which a minimum anode voltage produces anode current saturation, and rod-like electrodes independent of said control and auxiliary electrodes for directing electrons in a comparatively confined path toward said anode, said rod-like directing electrodes being positioned outside the area between the control electrode and its projection on said anode.

3. An electron discharge device comprising a cathode, an auxiliary electrode of substantially lenticular cross-section surrounding said cathode, a control grid of substantially lenticular cross-section positioned between said cathode and said auxiliary electrode, an anode of substantially cylindrical form surrounding said auxiliary electrode and being spaced therefrom by a distance approximating the critical distance at which the minimum anode voltage produces anode current saturation, and four rod-like electrodes inde-

pendent of said control and auxiliary electrodes spaced in pairs between said cathode and anode for directing the electrons in a comparatively confined path between each pair of rod-like electrodes toward said anode.

5. An electron discharge device comprising a cathode, an auxiliary electrode of substantially lenticular cross-section surrounding said cathode, a control grid of substantially lenticular cross-section positioned between said cathode and said auxiliary electrode, an anode of substantially cylindrical form surrounding said auxiliary electrode and being spaced therefrom by a distance approximating the critical distance at which the 10 minimum anode voltage produces anode current saturation, and four rod-like electrodes independent of said control auxiliary electrodes spaced in pairs between said auxiliary electrode and said anode for directing the electrons in a

comparatively confined path between each pair of rod-like electrodes toward said anode.

5. An electron discharge device comprising a cathode, an auxiliary electrode of substantially lenticular cross-section surrounding said cathode, a control grid of substantially lenticular cross-section positioned between said cathode and said auxiliary electrode, an anode of substantially cylindrical form surrounding said auxiliary electrode and being spaced therefrom by a distance approximating the critical distance at which the minimum anode voltage produces anode current saturation, and four rod-like electrodes spaced in pairs between said control electrode and said auxiliary electrode for directing 10 the electrons in a comparatively confined path between each pair of rod-like electrodes toward said anode. 15

JOHN HENRY OWEN HARRIES.
